THEODORE J. FLACK, OF BROOKSVILLE, FLORIDA.

APPARATUS AND PROCESS FOR CASTING.

Application filed October 14, 1927. Serial No. 226,171.

The present invention relates to the apparatus for and process for casting configurations and designs in metal or other fusible material, and has for an important object the 5 elimination of the necessity of making a separate pattern for the casting of each separate design.

A further object is to facilitate and cheapen the process of casting designs in metal.

10 Further objects are to provide a process whereby a multiplicity of varying designs may be cast by the use of stock patterns and to provide a process whereby such patterns may be combined in various designs.

15 In order to better understand the process forming the subject matter of this invention access to the accompanying drawings may be helpful, in which:

Figure 1 represents a frame for casting a 20 design, showing a design in place therein.

Figure 2 is a fragmentary view showing an additional element of the pattern in place above the elements shown in Figure 1.

25 Figure 3 is a section on the line 3—3 of Figure 1, showing the position of the sand within the flask above and surrounding the design.

Figure 4 is a fragmentary view of the drag, 30 showing the design as illustrated in Figure 1 as formed in the sand of the drag.

Figure 5 shows a third portion of the design placed above the configuration shown in Figure 4 and ready to be tapped in place to complete the design.

35 Figure 6 is a section on the line 6—6 of Figure 5, showing the channels made in the formation of the design and with the middle element of the design still within the channels.

40 Figure 7 shows in perspective the finished product of the process.

Referring to the drawings in detail, 45 10 designates the frame or drag of the flask which is to be set upon the bottom or board 11 and which is made up of the angular members 12 and 13 hinged together at 14 and latched together at 15 so that the drag may be removed from the bank of sand in which the mold is formed. The bottom or board 11, it 50 will be understood, is removable and there is provided the usual cope to cover the mold made in the drag by the pattern. A portion of the pattern is designated as a whole at 16 and consists of separate elements 17, 18 and 55 19 which may be laid on the board as shown in Figure 1, and an additional element 20

may be positioned thereon in the manner as illustrated in Figure 2. Pins or wires 21 may be utilized to connect the elements of the pattern together and to the board. 22 designates 60 the sand packed in the mold in which the configuration of the pattern is to be formed.

The process of molding by which the elimination of the making of a separate pattern for each design is brought about is as fol-

65 lows: The molder is provided with a plurality of elements, as for instance, letters of the alphabet, by which monograms formed of the initials of an individual, or of a society or firm, may be formed. Ordinarily in making 70 monograms of this character a separate pattern for each monogram must be first made, which entails the loss of a great deal of time and is done at a comparatively great expense.

It is proposed, according to the present process, to provide the molder with various letters of the alphabet and other configurations which may be combined to form a variety of 75 designs. In accordance with the illustrations in the drawings the process will be described 80 in connection with the use of letters, three letters being shown in the drawings which will suffice to illustrate, the letters being T, J and F. The letters T and F, which it will 85 be presumed are the first and last initials of the name of a person whose initial monogram is to be formed, are laid on the board 11 of a mold and a member 19 may be laid thereagainst to form part of the mold of the gate through which the molten metal flows into the 90

channels formed by the letters T and F. Let us presume that it is desired to place the middle initial J between the other two letters so as to overlap the same. This letter, design- 95

nated in the drawings by the numeral 20, is laid upon the patterns 17 and 18 disposed as described above upon the board 11. The 100

three letters are then clamped in place to avoid any chance of shifting, and holes are drilled as at 23 in Figure 2, said holes pref- 105

erably passing through at least two of the letters and at a point where, for instance, the letter J overlaps the same. There may be any number of these holes, as may be found con- 110

venient and desirable. These holes extend through the upper and lower letters and pref- 115

erably a short distance into the board and into these holes are inserted the wires or guide pins 21, after which the letter J is removed. The pieces of wire or guide pins are prefer- 120

and are inserted into the drilled holes. These wire are preferably of steel or hard brass and will hereinafter be referred to as guide pins. These guide pins form an important function in the invention as it is upon these holes and guide pins inserted therein that the process depends for its success.

After the pins are inserted with the three letters all in position as described above, the 10 top pattern, that is the letter J in the present instance, is lifted off the guide pins, leaving the pins and the other two letters in place and leaving the configuration as shown in Figure 1. The drag is then set on the board 15 and the gate forming member, which is of usual character and comprises a plug 22^a to be inserted to make connection with the channel formed by the member 19, is put in position, whereupon the mold is ready to receive the 20 sand which is poured into the mold and rammed down, filling the same. The drag is then rolled over, the board removed, and the cope put on and rammed with sand in the usual manner, after which the cope is lifted 25 off, the same presenting merely a flat surface. After the cope has been rammed full of sand it is removed from the drag and the patterns T and F are drawn out of the sand in the usual manner, leaving the channels 17^a and 30 18^a for the metal in the form of the letters T and F, as shown in Figure 4, and of the gate forming member 19^a, the guide pins remaining in place and protruding a short distance above the channels formed by the 35 letters T and F, whereupon the sand is moistened to form it and letter J is placed upon the sand with the guide pins projecting through the holes bored therein. It is obvious from the above description that the 40 letter will occupy the same position relative to the letters T and F that it occupied in Figure 2. The letter J may then be tapped down into the sand, making the impression of the added letter to the patterns of the previously made impression and in the identical 45 relationship to the other letters that it occupied in Figure 2. After the impression has been made and the upper surface of the letter J is flush with the upper edges of the 50 channels formed by the letters T and F, the letter J is likewise removed and the cope, which is of substantially the same construction as the drag and is not here shown, again placed upon the drag. The sand will yield 55 to this insertion of the third letter readily after it has been spread or sprinkled with water. Before closing the mold the guide pins are first pressed down into the sand to prevent the hot metal from burning the pins 60 into the casting.

By the above mechanism and process monograms and other configurations may be made

at a comparatively low cost and in a comparatively short time after the order has been placed.

65

Having described my invention, what I claim is:

1. A device for use in molding designs for metal, comprising a mold and a plurality of independent patterns adapted to be combined in a single pattern, guide means insertible through said independent patterns to connect them together and to locate the position of said independent patterns relative to each other, said patterns being removable from 70 said guide pins, and means for forming a gate to the channels formed by said patterns.

2. The process of molding designs having overlapping elements, consisting in first laying certain of the elements on a support and superimposing the overlapping element, drilling aligned holes through the elements at crossing points and into the support, placing guide members in the holes and removing the superimposed element, making a mold of the first named elements and removing said elements, moistening the mold, then placing the overlapping elements on the reverse side of the mold with the apertures thereof receiving the guide members, then removing the overlapping element, replacing the cope, and tapping it into the sand, then pouring metal 85 into the mold in the usual manner.

3. The process of molding designs having overlapping elements, consisting in laying 90 an element of the design on a support, and placing a second element in overlapping relation thereto, drilling holes through crossing points of the elements and into the support, placing guide members in said holes, removing the overlapping element, placing a form on the support, filling the form with mold taking material, inverting the mold, removing the support, removing the first named element, moistening the mold, placing the second named element on the mold with the guide members in the apertures thereof, tapping the second named element into the mold, removing the same, placing a cope on the mold and pouring the metal into the mold in 100 105 any well known manner.

4. A device for molding designs having overlapping elements, comprising a mold frame, a supporting board associated therewith, a plurality of elemental designs adapted to be used in overlapping relation, guide members for marking the overlapping positions of the elements, said elements having removable connection with said guide members, and means for taking the impression of 110 115 said elements.

In testimony whereof I affix my signature.

THEODORE J. FLACK.
